(57) **CLAIM**

The ornamental design for a taillight, as shown and described.

DESCRIPTION

FIG. 1 is a front perspective view of a taillight showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the taillight that form no part of the claimed design.

The oblique shade lines in the figures show transparency or translucency.
